CARTRIDGE EJECTOR

Bernard Maillard, Geneva, Switzerland, assignor to
 "Brevets Aero-Mecaniques," Geneva, Switzerland, a
 society of France

Application November 23, 1951, Serial No. 257,690

Claims priority, application Luxembourg
 November 25, 1950

1-Claim. (Cl. 42—25)

The present invention relates to firearms making use of cartridges, that is to say of rounds of ammunition including cartridge cases which are to be expelled from the arm after the shots are fired; and it is more particularly concerned with automatic arms because the problem of ejection is, in this type of arms, the more difficult to solve as the rate of fire is higher.

Its object is to provide an arm of this kind which is better adapted to meet the requirements of practice than those existing at the present time and in particular such that the operation of ejection of each cartridge case does not risk injuring this case in a manner detrimental of the good working of the arm.

It consists chiefly in constituting the ejector device essentially by two movable parts mounted like a pair of tongs, preferably in pivoting fashion, on the breech case of the arm on either side of the path of travel of the cartridge case when said cartridge case is moved rearwardly by the movable breech block, said parts being positively compelled by said movable breech block, during its recoil stroke, to move from retracted positions toward each other until they bear upon the body of the cartridge case and compel it to swing down by exerting thereon, through a squeezing action which lasts for a substantial portion of this turning period, a thrust perpendicular to the movement of the breech block.

Preferred embodiments of my invention will be herein-after described with reference to the accompanying drawings, given merely by way of example, and in which:

Figs. 1 and 2 show in horizontal section, respectively in two characteristic positions of its operation, a portion of the breech mechanism and in particular of the ejector system of an automatic arm according to my invention.

Figs. 3 and 4 show the same portion of the breech mechanism, respectively in sectional elevation and in cross section on the line IV—IV of Fig. 3, a plurality of successive positions occupied by the cartridge case in the course of the ejector phase being diagrammatically shown on these two figures.

Fig. 5 is a horizontal half section of a modification of my ejector system.

The invention will be described with reference to an automatic firearm the breech block of which is given a reciprocating movement to extract, after every shot has been fired, the empty case from the cartridge chamber of the arm, ejection proper being produced by the combined actions on said case of an extractor and of an ejector device.

The arm as a whole may be of any conventional design.

A barrel (not shown) is fixed to the end of a breech case 1 in which moves a breech block 2 adapted to keep, through its front edge, the cartridge in firing position when percussion is to take place.

The lower portion of the front edge of the breech block 2 carries an extractor 3 (Fig. 3) advantageously constituted by a pivotally mounted kind of hook which is partly retractable against the action of an elastic sys-

2

tem, said hook being adapted to engage into a circular groove 4a provided in the rear part of every case 4.

It will be readily understood that such an extractor supports the case 4 to be extracted and holds it applied against the front edge of breech block 2 during a first portion of the recoil stroke thereof (the direction of which is indicated by arrow F in Fig. 1), until the ejector device which will now be described enters into action.

According to my invention, this ejector device includes two movable parts mounted like a pair of tongs on breech box 1 on either side of the path of travel of cartridge case 4 and located above the level of the axis of the barrel (supposed to be horizontal), these movable parts being advantageously constituted by two ejector levers 5 pivoted about pins 6 rigid with the top wall of breech case 1 and perpendicular to said wall.

These ejector levers 5 are controlled by breech block 2, during its recoil stroke so that said levers leave, at a certain time, their retracted positions shown by Fig. 1, and their ends 5a located ahead of pins 6 move toward each other until they bear upon the body of the cartridge case 4 in zones thereof located above the horizontal plane passing through the barrel axis and substantially symmetrical to each other with reference to the vertical plane passing through said barrel axis.

The cartridge case will thus be compelled to swing down (the successive positions of said case in the course of this movement being shown by Figs. 3 and 4) due to the squeezing action to which it is subjected, which creates a continuous thrust perpendicular to the direction of the recoil movement of breech block 2, in which recoil movement cartridge case 4 participates as long as it is not disengaged from extractor 3.

Preferably, only the active stroke of the ejector levers 5 is positively controlled by breech block 2 during its recoil movement, said levers being returned into retracted position, during the forward return movement of said breech block, by elastic return means constituted, for instance, by two springs 7 inserted respectively between each side wall of breech box 1 and the rear branch of the corresponding ejector lever 5.

This positive control of the active stroke of each ejector lever 3 by breech block 2 may be obtained, in particular, either by causing an abutment rigid with said breech block to cooperate with an inclined surface of the lever to be controlled, or by providing the breech block with an inclined surface capable of cooperating, in cam-like fashion, with an abutment carried by the lever.

In the first case, according to a construction illustrated by Figs. 1 to 4, the curved inner edge of the rear branch of each ejector lever 5 is acted upon by the straight rear edge of a projection 2a carried by the upper rear face of breech block 2, each rear edge of this projection beginning to act upon the corresponding lever 5 as it passes opposite pins 6 (position shown by Fig. 1), then cooperating with the portion *o a* of the control inclined surface to bring the front end 5a of the lever into contact with cartridge case 4 and finally to compel, as said rear edge is moving along the rear portion *a b* of the control surface, the front end 5a of the lever to drive said case toward the outlet orifice 8 provided in the bottom wall of breech case 1 (intermediate position shown by Fig. 2).

In the second case, it is possible, for instance as shown by Fig. 5, to have the rear ends of ejector levers 5, advantageously provided with rollers 8, acting directly upon a double cam 2b carried by breech block 2.

It will be understood that it is possible to exert a certain influence upon the law of movement of the swinging down movement of case 4 by suitably choosing the transverse profile of the bearing surface of ends 5a (which surface acts as a push-cam during the transverse dis-

placement with respect to case 4) and/or the profile of the control cam *oab* (case of the embodiment illustrated by Fig. 5).

Account being taken of these possibilities, the swinging down movement of case 4 will be preferably accelerated positively during the whole time the ends 5a of the ejector levers 5 cooperate, in wedge-like fashion, with the body of case 4.

This ejector system swings down the empty cartridge cases and drives them out in a way comparable to what takes place when a cherry stone is squeezed between the thumb and forefinger.

An important advantage of my invention is that the ejector system acts upon the cartridge case by gradually squeezing it, without risk of deteriorating said case in such manner as would interfere with the good operation of the arm (projection of metal scraps into the breech mechanism, variation of direction of the ejection thrust due to local deformations of the sleeve, etc.).

Furthermore, it is well adapted to achieve an acceleration of the swinging down movement of the case during a substantial portion of the ejection phase, which makes it possible to increase the average speed of evacuation of said case, such a result being particularly interesting for firearms fitted on aircraft.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claim.

What I claim is:

In a firearm including a barrel, a breech case rigid with

5 said barrel, said breech case having an aperture in one wall thereof, and a breech-block and extractor slidably longitudinally in said breech case, a cartridge case ejector device which comprises, in combination, two 10 ejector levers pivoted intermediate the ends thereof to said breech case about axes perpendicular to the apertured wall, the axes being located symmetrically with respect to the plane of symmetry of said barrel perpendicular to the apertured wall and on either side thereof, said 15 ejector levers having their front ends located in a plane spaced from the barrel axis on the side of the axis opposite to that side on which the apertured wall is located and at a distance therefrom smaller than the radius of the cartridge case, upwardly and inwardly inclined cam surfaces on the front ends of said ejector levers, and cooperating cam means carried by said breech-block and the parts of said ejector levers located rearward of the pivot axes of the levers for driving said front ends of said levers toward each other and toward said plane of symmetry during the recoil stroke of said breech-block so that the cam surfaces on the ejector levers engage the cartridge case and guide the movement thereof as a component of the thrusts exerted by the ejector levers cause the cartridge case to pivot about the extractor and 20 be ejected from the firearm through the aperture in the wall of the breech case.
